CLAIM

The ornamental design for flooring as shown and described.

DESCRIPTION

FIG. 1 is a plan view of flooring of the present design.

FIG. 2 is a close-up plan view of the portion of the flooring marked 2 in FIG. 1.

FIG. 3 is a side view of the flooring of FIG. 1; and, FIG. 4 is a close-up side view of the portion of the flooring marked 4 in FIG. 3.

The dash-dash broken lines shown in the drawings illustrate portions of the flooring that form no part of the claimed design. The dot-dash broken lines represent boundaries of the enlarged views and form no part thereof.

1 Claim, 4 Drawing Sheets
